UNITED STATES PATENT OFFICE.

JOSEPH B. STRAUSS, OF CHICAGO, ILLINOIS.

BARRIER.

Application filed April 6, 1923. Serial No. 630,237.

This invention relates to barriers and has for its object to provide a new and improved device of this description. The invention has as a further object to provide a strong, durable and efficient movable barrier which may be lowered across the roadway to stop vehicles and which may be moved out of the way when it is desired to let the vehicles pass through. The invention has as a further object to provide an efficient and quick acting stopping mechanism for the obstructing device that extends across the roadway, when it is struck by a vehicle. The invention has other objects which are more particularly pointed out in the accompanying description.

Referring now to the drawings:

Fig. 1 is a front view of one form of the device embodying the invention.

Fig. 2 is an enlarged sectional view taken on line 2—2 of Fig. 1.

Fig. 3 is an enlarged view in part section showing the combined weight and brake.

Fig. 4 is a side view of the construction shown in Fig. 3.

Figure 5 is an enlarged sectional view taken on line 5—5 of Figure 4.

Like numerals refer to like parts throughout the several figures.

Referring now to the drawings;

I provide on each side of the roadway the posts or supports 1 which are preferably connected together by the brace 2. Extending across between the supports is a flexible obstructing device 3 which is engaged by the vehicle. This flexible obstructing device is connected at each end with a weight and a brake mounted in each support 1, the connection being made by flexible connections 4 or cables 4 which pass freely through openings in the sliding carriers 5 which slide up along the posts when it is desired to lift the obstructing device. These flexible connections 4 pass up the supports 1 and then pass around pulleys 6 at the top and then down over pulleys 7 connected with the weight 8 and then are fastened at their ends to the rods 9 which pass up through the cross piece 10 and are provided at their upper ends with the springs 11, the rods 9 having nuts or enlarged heads 12 so as to compress the springs when the obstructing device is struck by a vehicle. Each support is provided with similar flexible connections, pulleys and weights. When the obstructing device is

struck by a vehicle, these flexible constructions pay out through the holes in the sliding carriers 5 so as to let the vehicle move forward a predetermined distance. The flexible connections then exert a pull on the weight 8 and pull it up, the weight moving up at a slower speed due to the doubling back of the flexible devices. The weight tends to retard the movement of the obstructing device 3. Associated with the weight is a braking device which also acts to retard the movement of the obstructing device with an increasing resistance so that it will be gradually brought to a standstill, thereby preventing injury to the occupants of the automobile.

This braking device is illustrated in Figs. 3 and 4 and consists of suitable brake shoes 14 and 15 carried by the weight 8. When the weight is moved up, these brake shoes engage the brake members 16 and 17 attached to the supports 1. The brake shoes are preferably provided with removable non-metallic brake blocks 18. Means is provided for pressing the brake shoes against the brake members 16 and 17 as the weight moves up and of automatically releasing them when the weight stops so that the weight can drop back when the pressure on the obstructing device 3 is released. I provide one or more springs 20. In the drawings I have shown two such springs. These springs are located between the members 21 and 22 and tend to spread these members apart. The spreading apart of these members is limited by the limiting device 21 which, in this instance, are shown as bolts extending through the two members. The member 21 is connected to the brake shoe 14 by the link 23 and the member 22 is connected to the brake shoe 15 by the link 24. The link 23 is pivotally connected to the brake shoe by the pivot 25 and with the member 21 by the pivot 26, while the link 24 is connected to the brake shoe 15 by the pivot 25^a, and with the members 22 by the pivot 26^a. The pivots 25 and 26 are slightly out of alignment horizontally, the pivot 25 being somewhat higher up than the pivot 26, and the pivot 25^a being somewhat higher up than the pivot 26^a. The link 23 is connected to the brake shoe 14 by a spring 27 and the link 24 is connected to the brake shoe 15 by a spring 28. It will be seen from the foregoing that the brake shoes are mov^g 110

ably connected with the members 21 and 22 of both of the springs 20. Located below the brake shoes are stops 29 and 30. These stops are located as shown in Fig. 3, so that when the weight and the brake shoes are raised, the brake shoes engage the stops so that the pivots 25 and 25^a will remain slightly above the pivots 26 and 26^a so as to insure the release of the brakes as hereininafter set out. When the obstruction device is struck by a vehicle, it is moved out and this moves up the weight 8, the weight taking the first force of the blow and tending first to retard the movement of the obstructing device and the vehicle. As the weight moves up, the brake shoes engage the braking elements 16 and 17 and gradually stop the vehicle and the obstructing device. These braking elements may be of any desired length and I have shown them in Fig. 3, broken away. When the brake shoes engage the braking elements 16 and 17 they are moved down to engage the stops 29^a and 30 and this movement moves the parts 21 and 22 toward each other to compress the spring 20. During this upward movement of the brake shoe the pivots 25 and 25^a, are slightly above the pivots 26 and 26^a, by the stops 29 and 30. The springs 20 exert a pressure on the brake shoes to force them against the members 16 and 17. When the upward movement of the brake shoes is stopped, the friction tending to force the brake shoes downwardly and outwardly with relation to the members 21 and 22, is stopped and the brake shoes are free to move upwardly and inwardly thereby reducing the pressure against brake members 16 and 17 and leaving the weight free to drop when permitted to do so by the cables 4; that is, when the pressure on the obstructing device is released. In view of the fact that the outer ends of the links 23 and 24 are higher than the inner ends it will be noted that the springs 20 assist in releasing the brake shoes as the pressure thereof tends to further lift the outer ends of these links. When the pressure on the obstructing device is released, the weight and the brake shoes then drop back to their initial position. The bottom of the brake device then strikes the stops 31 and 32. These stops are somewhat higher than the stops 29 and 30 so that the brake shoes will fall back to their proper position with the pivots 25 and 25^a just slightly higher than the pivots 26 and 26^a, the device then being ready for the next movement. The springs 27 and 28 assist in securing the desired result. It will be noted that in this construction the springs 20 have opposite actions under certain conditions. During the upward movement of the brake device the springs press the brake shoes outwardly while when the upward movement stops, and the weight starts down this pres-

sure is relieved. It will therefore be seen that the pressure which the brake shoes exert on the parts 16 and 17 is controlled by the springs and may thus be properly regulated to meet the conditions presented. The 70 brake shoes and associated parts may be attached to the weight in any desired manner. As herein shown the weight is provided with the projections 34 and 35 at opposite sides thereof, the brake shoes and associated parts 75 being interposed between them. These projections are provided with grooves 36 into which loosely fit the projections 37 associated with the braking mechanism. The projections 37 are on the parts 21 and 22 and they 80 connect these parts and the springs with the weight. The brake shoes are connected with the projections 34 and 35 of the weight 8 through the links 23 and 24 and the parts 21 and 22. This is clearly shown in Figure 85 5. As shown in Figures 4 and 5 the grooves 36 are formed in separate pieces 37^a which are fastened to the projections on the weight 8 by bolts. This permits a sufficient amount of movement of the parts to secure the desired operation.

I have described in detail a particular construction embodying the invention but it is of course evident that the parts may be varied in many particulars without departing from the spirit of the invention as embodied in the claims hereto appended.

I claim:

1. A barrier comprising supports at the side of the roadway, an obstructing device adapted to extend across the roadway, a weight movably mounted in each support, flexible connections between the obstructing device and the weights and braking devices connected with said weights and moving therewith.

2. A barrier comprising supports at the side of the roadway, an obstructing device adapted to extend across the roadway, a weight movably mounted in each support, flexible connections between the obstructing device and the weights and braking devices connected with said weights and moving therewith, said braking devices provided with shoes, braking elements connected with the supports with which said shoes engage and means for automatically releasing the brake shoes when the movement thereof is stopped.

3. A barrier comprising supports at the side of the roadway, an obstructing device adapted to extend across the roadway, a weight movably mounted in each support, flexible connections between the obstructing device and the weights, brake shoes connected with each of said weights so as to move therewith, a spring interposed between said brake shoes, members between which said spring is located, pivoted links connecting said members with said brake shoes, the cen-

ters of the pivots being slightly out of horizontal alignment.

4. A barrier comprising supports at the side of the roadway, an obstructing device adapted to extend across the roadway, a weight movably mounted in each support, flexible connections between the obstructing device and the weights, brake shoes connected with each of said weights so as to move therewith, a spring interposed between said brake shoes, members between which said spring is located, a pivoted link connecting said members with said brake shoes, the centers of the pivots being slightly out of horizontal alignment and means for moving the parts to their starting position.

5. A barrier comprising an obstructing device adapted to extend across the roadway, a suspended weight in proximity thereto, a flexible connection between the obstructing device and the weight and a spring actuated braking device connected with said weight and moving therewith.

6. A barrier comprising an obstructing device adapted to extend across the roadway, a suspended weight in proximity thereto, a flexible connection between the obstructing device and the weight, a braking device connected with said weight and moving therewith, said braking device having two movable brake shoes, a spring interposed between them, braking elements engaged by said brake shoes, said spring acting to force the brake shoes against said braking elements when the weight is moving in one direction and means for causing said brake shoes to be released when the movement is stopped.

7. A barrier comprising an obstructing device adapted to extend across the roadway, supports at opposite sides of the roadway between which the barrier extends, a weight movably mounted in one of said supports, a flexible connection between said obstructing device and said weight, a brake connected with said weight so as to move therewith, said brake comprising separated movable brake shoes, braking elements adapted to be engaged by said brake shoes, separated members between the brake shoes and pivotally connected therewith, a spring between said separated members tending to force them apart and means for utilizing said spring to

assist in releasing the brake shoes when the weight stops.

8. A barrier comprising supports at the side of the roadway, an obstructing device adapted to extend across the roadway, a weight movably mounted in each support, flexible connections between the obstructing device and the weights, brake shoes connected with each of said weights so as to move therewith, separated braking members between which the brake shoes are moved when the obstructing device is struck, a spring interposed between said brake shoes, members between which said spring is located, pivoted links connecting said members with said brake shoes, the centers of the pivots being slightly out of horizontal alignment whereby said spring tends to force the brake shoes against said braking elements, means for releasing the brake shoes when the upward motion thereof is stopped and means for returning the links and pivots to their initial position when the weight and brake are lowered.

9. A barrier comprising supports at the side of the roadway, an obstructing device adapted to extend across the roadway, a weight movably mounted in each support, flexible connections between the obstructing device and the weights, brake shoes connected with each of said weights so as to move therewith, separated braking members between which the brake shoes are moved when the obstructing device is struck, a spring interposed between said brake shoes, members between which said spring is located, pivoted links connecting said members with said brake shoes, the centers of the pivots being slightly out of horizontal alignment whereby said spring tends to force the brake shoes against said braking elements, means for releasing the brake shoes when the upward motion thereof is stopped, stops for said weight by means of which the brake shoes are brought into their proper initial position when the weight reaches the lower limit of its movement.

Signed at Chicago, county of Cook and State of Illinois, this 19th day of March, 1923.

JOSEPH B. STRAUSS.
